C. MOHAR,
CLOTHES LINE SUPPORT,
APPLICATION FILED DEC. 20, 1915.

1,285,311.

Patented Nov. 19, 1918.

UNITED STATES PATENT OFFICE.

CARL MOHAR, OF SHEBOYGAN, WISCONSIN.

CLOTHES-LINE SUPPORT.

1,285,311.

Specification of Letters Patent. Patented Nov. 19, 1918.

Application filed December 20, 1915. Serial No. 67,703.

To all whom it may concern:

Be it known that I, CARL MOHAR, a citizen of the United States, and resident of Sheboygan, in the county of Sheboygan and State of Wisconsin, have invented certain new and useful Improvements in Clothes-Line Supports; and I do hereby declare that the following is a full, clear, and exact description thereof.

10 My invention has for its object to provide a simple, useful, economical and effective collapsible line especially adapted for use in connection with drying clothes, the construction and arrangement being such 15 that the apparatus as a whole, while operating in a minimum space will have a maximum capacity.

With the above object in view the invention consists in certain peculiarities of construction and combination of parts as hereinafter set forth with reference to the accompanying drawings and subsequently claimed.

In the drawings

25 Figure 1 represents an elevation of a clothes drying apparatus embodying the features of my invention, the same being shown in its distended or full operating position;

30 Fig. 2, a detailed cross-section of the shackle mechanism for confining the line to a post or column, the section being indicated by line 2—2 of Fig. 3, and

35 Fig. 3, a detailed sectional view of a windlass mechanism employed in carrying out my invention, the section being indicated by line 3—3 of Fig. 1.

Referring by characters to the drawings, 1, 1, represent vertical posts which constitute rail members and under ordinary conditions 40 are arranged to be, for example, of considerable height or in such proportions to the details that an animal or person can pass under the lowest strand of the apparatus without interference and, in practice, the 45 windlass actuating mechanism may be so low to the ground that animals or persons can safely step over the same.

It should be understood that in the exemplification of my invention, while I have 50 shown posts for supporting the drying rigging, I may, in some instances, employ rails which may be attached at their top and bottom to the sides of buildings or other points of anchorage and that these rails may be 55 vertically or horizontally disposed as, for example, in high tenement buildings the ap-

paratus may be positioned vertically and accessible from the windows, whereby the washing may be conveniently attached and the apparatus run out to a full distended 60 position, as shown in Fig. 1.

2, 2, represent companion sets of clips which encircle the posts, the ends of the clips being rearwardly connected by concavo-convexed rollers 2', which are adapted to track 65 upon the posts or rail members. Each clip member pivotally carries a three-armed block 3 having triangularly disposed apertures therein. One set of the apertures are connected by runners 4 constituting clothes line 70 sections, the same being fastened to the blocks 3 by spring snaps of any standard type. The runners or lines may be composed of any desired material such as galvanized wire, cables, cotton rope, or the like. 75

The series of blocks are cross-connected by tie-cables 5 having snap-hooks for engagement with the eyes of the blocks and the outer companion blocks indicated at α are connected to the ends of hoisting cables 6 80 by suitable snap hooks. These cables are passed over guide sheaves 7 which are suitably journaled upon studs carried at the ends of the posts 1, the said sheaves, as shown, being fitted into apertures formed in 85 the post ends. The hoist cables are extended downwardly and engage and are guided by the several rollers 2' of the clip connections, the inner ends of said cables being secured to and coiled about companion drums 8, 8', 90 which drums are fast to a shaft 9. The shaft is journaled in bearing brackets 9' that are secured to the inner or lower ends of the posts, as shown, and the drum 8' carries a ratchet-wheel 10, which is engaged by a 95 spring-controlled dog 11 that is provided with an arm 11', whereby the said dog may be manually disengaged from the ratchet-wheel. The shaft 9 is also provided with a crank 9'' in juxtaposition to the drum 8', 100 whereby the windlass mechanism just described is manipulated. 12, 12, represent stop-blocks for engagement with the clip rollers 2', whereby the various stretches of the clothes line are nested at a convenient 105 point for loading the same.

When the apparatus is positioned to operate vertically, as shown in the drawings, in order to load each of the line stretches with washing, the dog 11 is manipulated to 110 permit the drums to unwind the hoisting cables 6, whereby the first line of the series

will drop down and be stopped by the blocks 12. This nesting of the first line will be followed by the second line and so on through the series until the entire set of line 5 sections are brought to a common point. The first line is then loaded and thereafter it is drawn up clear of the nested series from which the second line is now lifted and similarly loaded, the latter being then drawn 10 clear of the third and so on throughout the entire series until the several stretches of line are all set with the washing, at which time the apparatus will be suspended as shown in the drawing and locked in its 15 suspended position by the dog 11 which engages the controlling ratchet-wheel 10.

It is obvious that, should the line be rigged for horizontal operation, I may connect the lower block y with pull runners, 20 which runners may be snapped into the unoccupied eyes of said blocks, whereby the last stretch of the line can be drawn in toward the window coincident to release of the windlass mechanism.

25 It is also manifest that the rigging may be provided with as many line units as the case may require by adding companion clips or subtracting them from the series.

I claim:

30 A support of the class described and for the purpose specified comprising a pair of parallel supporting members having their outer sides transversely curved throughout their length, a sheave journaled in the end 35 of each supporting member, a like number of yokes embracing each supporting mem-

ber, a plurality of three-armed blocks having an aperture in the end of each arm, each of said blocks pivoted midway the apertures therein to the inner portion of each yoke, a 40 longitudinally concaved roller on the outer portion of each yoke and shaped for engagement with the transversely curved portions of the supporting members, a line connected with each companion pair of blocks 45 by means of the inwardly extending apertured arms thereof, a flexible operating member disposed around each of said sheaves and having one end fixed to the outwardly extending arm of each outermost 50 block, a winding mechanism on each supporting member adjacent the supporting end thereof and having the other ends of said flexible operating members disposed therearound, said flexible operating members being disposed in the concaved portions 55 of the rollers and guided thereby, a connecting line of predetermined length detachably secured to the adjacent arms of each adjacent pair of blocks, whereby connecting lines of different lengths may be used to space the blocks different distances apart, and means for limiting the downward movement of the yokes.

In testimony that I claim the foregoing I 65 have hereunto set my hand at Sheboygan in the county of Sheboygan and State of Wisconsin in the presence of two witnesses.

CARL MOHAR.

Witnesses:

PETER STORBOR,
ANTON STARICH.
